UNITED STATES PATENT OFFICE

GEORGE D. SHAEFFER, OF BUCYRUS, OHIO, ASSIGNOR TO W. A. RIDDELL COMPANY,
OF BUCYRUS, OHIO, A CORPORATION OF OHIO.

GRADER

Application filed November 5, 1931. Serial No. 573,103.

This invention, relating as indicated to road graders, has particular reference to a type of apparatus which normally carries a so-called scraper blade which, when such apparatus moves over the road, presents the blade in operable relation at various positions and angles to the surface of the roadway or the adjacent ditches and banks.

More particularly, my invention relates to a form of construction characterized by the employment of a substantially tubular reach member extending from the rear truck to the front truck of the apparatus connecting the same and operably supporting the working implement of the machine.

As is well known to those familiar with the art, the above described type of road grader is required to present the operating blade or tool at various angles to the work, both horizontal and vertical. No particular difficulty has been experienced in the past in the adjustment of the earth working implement in a horizontal plane, which adjustment is usually made for the purpose of regulating the manner in which such tool fills depressions in the surface operated upon or delivers quantities of material laterally of the machine.

With a more universal use, however, of the common form of road grader for the purpose of performing numerous operations such as cutting away banks, cleaning out ditches and the like, previously accomplished by manual labor, the need has arisen for a grader in which the blade or earth working tool is capable of adjustments in a vertical plane not possible with constructions heretofore employed.

In my invention, which is presently to be described, I have adapted the type of road grader employing a tubular reach to make possible the above identified adjustments easily and efficiently and with a further realization of advantages of this type of construction heretofore never appreciated. It is among the objects of my invention to provide a form of construction having the above named desirable characteristics. Other objects of my invention will appear as the description proceeds.

To the accomplishment of the foregoing and related ends, said invention, then consists of the means hereinafter fully described and particularly pointed out in the claims.

The annexed drawings and the following description set forth in detail certain mechanism embodying the invention, such disclosed means constituting, however, but one of various mechanical forms in which the principle of the invention may be used.

In said annexed drawings:

Fig. 1 is a plan view of the apparatus comprising my invention; Fig. 2 is a front elevational view of such apparatus; Fig. 3 is a rear elevational view; Fig. 4 is a broken, part sectional, part side elevational view of the apparatus disclosed in the previous figures; Fig. 5 is an enlarged part sectional, part plan view of the apparatus illustrated in Fig. 1; Fig. 6 is a broken, part sectional, part plan view of a portion of the apparatus illustrated in the previous figures drawn to an enlarged scale; Fig. 7 is a broken side elevational view of the apparatus illustrated in Fig. 6; Fig. 8 is a transverse sectional view of the implement supporting circle and its associated mechanism; Fig. 9 is a fragmentary, sectional view of the portion of the manipulating apparatus employed in my construction; Fig. 10 is a transverse sectional view of a portion of the apparatus illustrated in Fig. 9 taken on a plane substantially indicated by the line 10—10; and Fig. 11 is a fragmentary sectional view of the means for supporting the manipulating shaft illustrated in Fig. 9 in any one of three selected positions.

Referring now more specifically to the drawings and more particularly to Figs. 1 to 4, the apparatus comprising my invention may be generally described as comprising a front truck generally indicated at 1, a rear truck generally indicated at 2, which trucks are connected by means of a tubular reach pipe 3. A draft pole 4 secured to the front truck 1 by means hereinafter more fully explained, will be hitched in a suitable fashion to some means for moving the grader across the ground.

The reach pipe 3 is, at its forward end, as most clearly illustrated in Fig. 4, secured to a suitable bracket 5 which has a forward annular extension 6 which is preferably formed in sections so as to enable the same to be bolted around a substantially spherical casting 7 forming a part of the front standard of the device. Associated with and removably secured to the annular extension 6 is a complementary member 8 which, when bolted or similarly secured to the member 6, universally connects the forward end of the reach pipe 3 to the casting 7.

The casting 7 has a forward extension 9 securing the rear end of the draft pole 4 and the rear end of such casting, at its lower portion, serves as a means of support for a swivel member 10 which, as hereinafter more fully explained, transmits the pull from the draft pole 4 directly to the earth working implement without subjecting the frame of the machine to undue internal stresses. The rear end of the reach pipe 3 is carried in a plate 11 which is secured to substantially vertically disposed frame members 12 and thereby supported on the rear truck in the manner most clearly illustrated in Fig. 4.

From the foregoing description of the skeleton frame work of the machine, it will be noted that the front and rear trucks are interconnected only by means of a tubular member which reduces to a very minimum the intermediate width of the machine so that the earth working implement carried thereby may be moved about in a vertical plane without encountering any obstruction such as side frame members employed in former types of construction.

The wheels 13 on the front truck and the wheels 14 on the rear truck are mounted on axles capable of oscillation in a transverse plane so as to enable the apparatus to operate as a leaning wheel gear, the advantages of which are well known to those familiar with the art.

The wheels 13 of the forward truck are adjusted in the manner described by links 15 which are oscillatably secured to a lever 16 oscillated by mechanism contained within a gear box 17 carried in the front truck. The actuating shaft 18 for this gear box is disposed vertically within the front standard and has a bevel gear 19 keyed to its upper end. A horizontally disposed rotatable shaft 20 journaled in the cap 21 of the front standard carries a bevel pinion 22 which meshes with the gear 19 so that upon rotation of the shaft 20, rotation of the shaft 18 will occur and consequent manipulation of the links 15 to effect the proper leaning of the front wheels. A shaft 23 is universally coupled to the shaft 20 and extending rearwardly through the reach pipe 3 has a hand-wheel 24 keyed thereto so that by rotating this

hand-wheel, the wheels 13 on the front truck may be oscillated in a vertical plane.

Referring more specifically to Fig. 3, it will be noted that links 15' are provided on the rear truck which are connected to a crank arm 16' of a gear box 17' for the purpose of effecting a leaning of the rear wheels similarly to the wheels of the front truck. The mechanism within the gear box by which the crank arm 16' is oscillated is actuated by a vertically disposed shaft 25 which carries a hand-wheel 26. As most clearly illustrated in Fig. 1, the rear truck 2 may be shifted transversely with respect to the longitudinal axis of the reach pipe 3 by means of a rack 27 and pinion 28, such pinion being actuated by a vertically disposed shaft 29 carrying a hand-wheel 30. The above described construction of the front and rear trucks of the machine forms no particular part of this invention other than supplementing the major features of my design which are presently to be described to produce a complete operable structure. The detailed construction of the front and rear trucks has not been shown in an enlarged scale on the drawings, inasmuch as the particular apparatus and controls therefor for producing a leaning of the several wheels of the machine, as well as a shifting of the rear truck transversely of the axis of the machine, are common forms of construction employed in numerous machines in the prior art so that this portion of the apparatus will not be described nor disclosed in greater detail.

As previously indicated and as most clearly illustrated in Fig. 4, the earth working tool which, in this particular case has been illustrated as a scraper blade 31, is carried by the common form of bracket 32 secured to and depending from a circle member 33. The circle 33 is rotatably supported on a pin 34 depending from a frame 35. The frame 35 is, at its forward end, connected to and supported by the swivel 10 which transmits the load directly to the draft pole 4.

As most clearly illustrated in Fig. 6, the circle member 33 is, at the forward portion of its periphery, provided with a plurality of teeth 36 adapted to be engaged by a latch 37 which is oscillatably supported in a bracket 38. The latch 37 has secured thereto an upwardly extending bracket 39. A retractive spring 40 normally urges the latch 37 into engagement with the teeth 36. The latch may be moved out of engagement by means of a tension member 41 which, at its forward end, is secured to an oscillatable link 42. The link 42 has a manipulating member 43 secured thereto and which extends rearwardly and may enter the reach pipe through a suitable aperture provided therefor, so that it will not interfere with the ma-

nipulation of the means supporting the blade 31. The member 43 may extend rearwardly out of the reach pipe and be provided with suitable means whereby through the train 5 of linkage above described, the latch 37 may be moved into and out of engagement with the teeth 36, so that the circle 33 may be moved circumferentially relatively to its supporting frame and after being moved, maintained in such adjusted position.

The means for adjustably supporting the circle which carries the earth working implement will now be described and it is this apparatus alone and in combination with the 15 previously described features of my machine and those features which will in addition be described, which constitutes the major portion of my invention.

The reach pipe 3 has mounted thereon two 20 concentric sleeves 44 and 45, such sleeves being carried by suitable friction reducing bearings. The outer sleeve 44, as most clearly illustrated in Figs. 1 and 5, has secured thereto a radially extending arm 46 and the inner sleeve 45 carries a similar radially extending arm 47. As most clearly illustrated in Fig. 2, the radial arms 46 and 47 respectively have secured thereto depending links 48 and 49 which, at their lower ends, 25 are connected to the implement supporting circle. Rotation of either sleeve 44 or 45 will, therefore elevate one side or the other or both sides of the grader blade. A third sleeve 50, as most clearly illustrated in Fig. 25 4, is carried on the reach pipe and such sleeve has oscillatably secured thereto a cross shift link 51 which, at its lower end, is oscillatably in engagement with a portion of the implement supporting circle. By the proper circumferential shifting of the several sleeves, the grader blade may be made to assume any 30 position in the vertical plane with respect to the reach pipe. With proper clearance under the machine, it will be noted that the 35 grader blade can be swung around the reach pipe to assume a vertical position so that the machine might be used for the purpose of working along a vertical bank if this operation should be required to be performed. 40 Manipulation of the sleeves 44 and 45 and consequent elevation or lowering of the grader blade is accomplished by means of the hand-wheels 52 and 53. These hand-wheels are keyed to shafts 54 and 55 which, at their 45 inner ends, as most clearly illustrated in Fig. 5, respectively carry worm gears 56 and 57. The worm gears 56 and 57 are respectively in mesh with worm gears 58 and 59 secured to the outer periphery of sleeves 44 and 45. 50 Relative circumferential movement between the sleeve 50 and the reach pipe 3 is effected by means of a gear 60 carried by such sleeve, a worm 61 in mesh therewith which is mounted on a shaft terminal carrying a bevel pinion 62. The bevel pinion 62 is in mesh

with another bevel pinion 63 carried on the extension universally connected to the end of a shaft 64. The shaft 64 is, at its rear end, universally coupled to an extension shaft 65 journaled in a gear box 66.

The gear box 66 has three parallel shafts 65, 67 and 68 journaled therein. The center shaft 67 extends rearwardly out of the gear box and has a hand-wheel 69 secured thereto. Shafts 65 and 68 have gears 70 and 71 keyed thereto with which the pinion 72 carried by the center shaft 67 may selectively mesh. In axial alignment with the center shaft 67 is a sleeve 73 which has secured thereto, as most clearly illustrated in Fig. 10, a splined member 74 with which the terminal 75 of the shaft 67 may co-operate so that such sleeve may be rotated by such shaft as the same are moved axially into engagement.

The sleeve 73 is universally connected to the forward end of a shaft 76 which, through a shaft 77, and a gear train generally indicated at 78, is adapted to rotate a pinion 79 in mesh with a gear segment 80. The gear segment 80 is pivotally supported and connected to the front truck of the machine by means of links 81. When the hand-wheel 69 is moved axially inwardly until the shaft 67 and the sleeve 73 are in engagement, then a rotation of such hand-wheel will effect a steering of the front 95 wheels of the grader.

It will be noted that the shaft 67 is provided with a plurality of axially spaced circumferential grooves 82, 83 and 84 and the wall of the gear casing is provided with a resiliently supported ball 85 for engagement with any one of such grooves to maintain the shaft 67 in any one of its axially adjusted positions. When the shaft is retracted in the position illustrated in full lines in Fig. 9, rotation of the hand-wheel 69 will effect a rotation of the shaft 65 which, as previously indicated, is arranged to manipulate the link 51 and accordingly move the grader blade transversely of the machine. When, however, the shaft 67 is moved axially so that the hand-wheel occupies the dotted line position indicated at 86, the pinion 72 will be out of mesh with both gears 70 and 71 but the shaft will be in engagement with the sleeve 73 so that the hand-wheel 69 may be employed as a steering wheel without effecting the set of the grader blade. When the shaft is moved axially for a further distance to the dotted line position illustrated at 87, then the terminal 75 thereof will be out of engagement with the splined member 74 but the pinion 72 will be in mesh with the gear 71 so that a rotation of the hand-wheel will effect a rotation of the shaft 68.

The shaft 68 will preferably be connected by means of suitable shafts and universal couplings to means for adjusting the position of a second earth working tool such as a scarifier which, however, is not illustrated in the drawings.

For the purpose of effecting adjustment of the grader blade in a horizontal plane, the rear circumferential portion of the circle 33 is provided with a plurality of teeth 88 with which, as most clearly illustrated in Fig. 7, a pinion 89 meshes. The pinion 89 is keyed to a shaft which, at its upper end, has a bevel pinion 90 keyed thereto which meshes with a second bevel pinion 91 keyed to a third shaft 92. The shaft 92 is rotated by means of a flexible connection 93 leading to a shaft 94 on which is mounted a hand-wheel 95. The shaft 94 is journaled in a suitable bearing supported in a bracket 96 secured to the lower edge of the plate 11. The purpose of the flexible connection 93 is to permit relative movement between the circle supporting gear blade and the frame of the gear without interfering with the operation of the means for adjusting the blade in a horizontal plane.

It will be noted that the above described form of construction has numerous advantages not found in any constructions heretofore employed and which may be briefly enumerated as follows:

The employment of a tubular reach for the grader affords a compact connection between the front and rear trucks which is exceptionally rigid. This tubular reach also serves as a bearing for the several sleeves which, when rotated relatively thereto, may be employed for the purpose of effecting a selected movement of the linkage supporting the earth working implement so that the support of such tool is greatly simplified. As above indicated, due to the fact that the tubular reach of the grader is also the means of rotatably supporting the linkage which carries the blade, the grader blade may be swung about the axis of the reach pipe to any desired working angle. This substantially universal movement of the frame supporting the blade is further made possible by means of the swivel connection between such frame and the front truck or draft pole of the grader. A further desirable advantage of the construction comprising my invention is that the entire thrust of the blade is carried through its immediate supporting frame and transmitted directly to the draft pole without subjecting the frame of the machine to any of this stress. The tubular reach may also be employed for the purpose of supporting a forward operating tool, such as a scarifier, if mounted so as not to interfere with the means supporting the scraper blade. It is believed that the operation of the above described form of construction and the advantages incidental to the same are sufficiently evident to those familiar with the prior art that a further description thereof is unnecessary.

Other modes of applying the principle of my invention may be employed instead of the one explained, change being made as regards the mechanism herein disclosed, provided the

means stated by any of the following claims or the equivalent of such stated means be employed.

I, therefore, particularly point out and distinctly claim as my invention:

1. In apparatus of the character described, the combination of a wheel supported tubular reach member, an earth working tool, and means concentric with and rotatable relatively to said reach for supporting said tool.

2. In apparatus of the character described, the combination of a wheel supported tubular reach member, an earth working tool, and a member journaled on periphery of said reach for adjustably supporting said tool.

3. In apparatus of the character described, the combination of a wheel supported tubular reach, an earth working tool, and a plurality of tool supporting members rotatably supported concentrically on said reach.

4. In apparatus of the character described, the combination of a wheel supported tubular reach, an earth working tool, a plurality of concentric sleeves rotatably supported on said reach for supporting said tool, and means operable from a central station for effecting rotation of said sleeves relatively to said reach.

5. In apparatus of the character described, the combination of a wheel supported tubular reach, an earth working tool, a plurality of sleeves concentric with and journaled on said reach for supporting said tool and moving the same in a vertical plane, and means for relatively rotating said sleeves and said reach.

6. In apparatus of the character described, the combination of a wheel supported tubular reach, an earth working tool, members journaled on said reach respectively adjustably supporting opposite sides of said tool and a further member journaled on said reach adjustably supporting said tool for movement independently of said first named supporting means.

7. In apparatus of the character described, the combination of a wheel supported tubular reach, an earth working tool, sleeves journaled on said reach respectively supporting opposite portions of said tool for vertical adjustment, and another sleeve journaled on said reach supporting said tool for adjustment transversely of said reach.

8. In apparatus of the character described, the combination of a wheel supported tubular reach, an earth working tool, means journaled on and concentric with said reach adjustably supporting said tool in a plane transversely of the axis of said reach, and means for swinging said tool to adjust its angular relation to said plane.

9. In apparatus of the character described, the combination of a wheel supported tubular reach, an earth working tool, means journaled on the periphery of said reach ad-

justably supporting said tool in a plane transversely of said reach, means for adjustably rotating and supporting said tool in angular relation to said plane, and means for securing said tool in its adjusted position.

10. In apparatus of the character described, the combination of a wheel supported tubular reach, a draft pole, an earth working tool coupled to the end of said draft pole, and a plurality of sleeves concentric with and journaled on said reach for adjustably supporting said tool.

11. In a road grader having front and rear trucks, a tubular reach connecting said trucks, a draft pole associated with the front truck, an implement carrying frame coupled to said pole, and a plurality of sleeves concentric with and journaled on said reach adjustably supporting said frame.

12. In a road grader having front and rear trucks, a centrally arranged longitudinally extending reach member connecting said trucks, a draft pole associated with one of said trucks, an implement frame coupled to said pole, and a plurality of sleeves concentric with and journaled on said reach member adjustably supporting said frame.

13. In a road grader having front and rear trucks, a centrally arranged longitudinally extending reach member connecting said trucks, an implement carrying frame, means for rotatably supporting an implement on said frame, a plurality of sleeves concentric with and journaled on said reach member adjustably supporting said frame, and means for relatively rotating said implement and frame.

14. In a road grader having front and rear trucks, a centrally arranged longitudinally extending reach member connecting said trucks, an operator's station on one of said trucks, an implement carrying frame movably secured at one end to one of said trucks, a plurality of sleeves concentric with and journaled on said reach member adjustably supporting said frame, an implement rotatably supported on said frame, and means operable from said operator's station for relatively moving said frame and reach member and said implement and frame.

15. A road grader having in combination front and rear wheeled trucks, a tubular reach member mounted on the rear truck and universally connected to the front truck, means for steering the wheels of one of said trucks, an implement carrying frame oscillatably coupled to one of said trucks, an implement rotatably supported on said frame, a plurality of sleeves concentric with and journaled on said reach member for adjustably supporting said frame, and means for relatively rotating said implement and frame, all of said steering and implement adjusting means being operable from a single station.

16. A road grader having in combination front and rear wheeled trucks, a tubular reach member mounted at one end on one of said trucks and universally coupled at its other end to the other truck, an implement carrying frame oscillatably coupled to one of said trucks, a sleeve journaled on said reach member and having a radially extending arm connected to one side of said frame, a second sleeve journaled on said reach member and provided with a radially extending arm connected to the other side of said frame, means for independently rotating said sleeves whereby either side of said frame may be raised or lowered, a third sleeve journaled on said reach member and provided with a connection to said frame whereby rotation of said third sleeve will effect a lateral shifting of said frame, all of said sleeves arranged substantially concentric with said reach, an implement supporting circle on said frame, and a flexible operating device extending from said operator's station to said frame whereby said circle member may be rotated.

Signed by me this 2nd day of November, 1931.
